* cited by examiner

Primary Examiner — Elizabeth J Oswecki(74) Attorney, Agent, or Firm — Renner, Otto, Boisselle & Sklar, LLP(57) CLAIM

The ornamental design for a wreath, as shown and described.

DESCRIPTION

FIG. 1 is a perspective view of a wreath showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the drawings represent portions of the wreath that form no part of the claimed design.
